(57) **CLAIM**

The ornamental design for a drying rack, as shown and described.

DESCRIPTION

FIG. 1 is a top front isometric view of a drying rack showing the new design.

FIG. 2 is a bottom back isometric view of the drying rack in FIG. 1.

FIG. 3 is a front view of the drying rack in FIG. 1.

FIG. 4 is a back view of the drying rack in FIG. 1.

FIG. 5 is a right side view of the drying rack in FIG. 1.

FIG. 6 is a left side view of the drying rack in FIG. 1.

FIG. 7 is a top view of the drying rack in FIG. 1; and,

FIG. 8 is a bottom view of the drying rack in FIG. 1.

The details shown in broken lines illustrate portions of the drying rack that form no part of the claimed design.

1 Claim, 8 Drawing Sheets
